UNITED STATES PATENT OFFICE.

WILLIAM BAYLEY, OF SPRINGFIELD, OHIO.

SILO.

Application filed January 26, 1926. Serial No. 83,886.

My invention relates to silos and more particularly to a sheet metal silo construction affording a vertical succession of closely disposed access or door opening, affording the 5 approximate advantages of a continuous opening, while providing maximum reinforcement against excessive internal pressure, bursting and shearing strain.

In the usual form of sheet metal silo construction, the metal sheets are arranged in horizontal or annular courses, the alternate courses being interrupted to afford spaced access or door openings.

This disposition of the access openings, not 15 only separates the openings too far for convenient handling of ensilage but it also weakens the silo structure, causing excessive strain to be imposed upon the alternate courses of wall sheets which pass intermediate the door 20 openings.

In the present invention, there is contemplated a construction wherein the internal pressure or bursting strain will be distributed throughout the succession of circular or horizontal courses of wall sheets, so that each succeeding course will resist its proportionate degree of the strain and stresses, while at 25 the same time permitting the access openings or door openings to be brought quite closely together and separated by merely a comparatively narrow tie member. This is effected by making each and every course continuous throughout the periphery of the silo, but reducing in height and reinforcing 30 each course to resist buckling adjacent to the door or access opening position, across which the ends of the course are interconnected by a comparatively narrow tie member, which, however, is so designed and proportioned as 35 to resist the stresses and strains equally with the fully dimensioned wall sheets of the course. In the preferred embodiment of the invention as hereinafter described and illustrated in the drawing, each course of wall 40 sheets is tapered or beveled at its ends adjacent to the access opening, preferably by folding the corners of the wall sheets backward upon themselves to parallelism to form convergent extremities which may be reinforced 45 by additional tapered reinforcement plates. The reinforced tapered ends are interconnected by an intermediate tie bar, preferably of channel form, which narrowly separates the 50 vertical succession of access or door openings 55 one from the other.

The object of the invention is to simplify the structure as well as the means and mode of assembly, or erection of sheet metal silos, whereby they will not only be cheapened in construction, but will be more efficient in use, 60 of increased strength and durability, capable of affording maximum resistance to bursting and shearing strain and otherwise unlikely to get out of order.

A further object of the invention is to provide a silo construction, having a succession of closely associated access or door openings, without materially weakening the structure and wherein the resistance to internal bursting strain, as well as wind pressure will be 70 uniformly distributed.

A further object of the invention is to provide an improved form of interlocking the successive wall sheets one with another to enable them to resist the shearing strain induced by internal pressure.

A further object of the invention is to provide an improved form of reinforcement of sheet metal silos and to provide a silo construction which may be quickly and economically assembled or erected by unskilled laborers.

With the above primary and other incidental objects in view as will more fully appear in the specification, the invention consists of the features of construction, the parts and combinations thereof, and the mode of operation or their equivalents as hereinafter described and set forth in the claims.

Referring to the accompanying drawings, 90 wherein is shown the preferred, but obviously not necessarily the only form of embodiment of the invention, Fig. 1 is a top plan view of a sheet metal silo, embodying the present invention, the roof or cover being removed. 95 Fig. 2 is a vertical sectional view, of the assembled silo on line 2-2 of Fig. 1. Fig. 3 is an enlarged front elevation of a portion of the silo structure showing one of the access or door openings, and the interconnected reinforced adjacent ends of succeeding wall sheet courses. Fig. 4 is a detail plan view. Fig. 5 is a detail view illustrating the manner of folding the ends of successive wall sheet courses to afford the tapered reinforced extremities. Figs. 6 and 6^a illustrate the reinforcement plate for the interconnected ends of the successive courses or wall sheets. Fig. 7 is a detail view of the transverse interconnection by which successive courses of wall 100 105 110

sheets are interconnected intermediate the access or door opening. Fig. 8 illustrates in several aspects the hinge block to be attached to the inner face of the tie bar, from which 5 the closures or doors are suspended. Figs. 9 and 10 show mere modifications of the reinforcement bead or flange for the plate shown in Fig. 6. Fig. 11 is a detail view of a modification wherein only one corner flap of the 10 contiguous ends of wall sheet courses are reversed. Fig. 12 is an elevation of a portion of the structure showing the access opening formed at spaced intervals by the construction shown in detail in Fig. 11. Figs. 13 to 15 illustrate a further modification wherein 15 the access or door opening is formed entirely within the height of a single course of wall sheet. Fig. 13 is a detail view from the interior of the structure, showing the relation 20 of the reversed triangular flap and the reinforcement plate. Fig. 14 is a front elevation illustrating the assembly of parts as viewed from the exterior. Fig. 15 is a detail sectional plan view of the structure shown in 25 Fig. 14.

Like parts are indicated by similar characters of reference throughout the several views.

The present silo construction involves a cylindrical tank like structure, having in one 30 side thereof, a vertical succession of access openings or doors. The side walls of the silo comprise a succession of annular or peripheral courses of sheet metal wall sheets, each comprising a plurality of such sheets interconnected to each other, by being riveted or bolted together through outstanding vertically disposed flanges. The wall sheets comprising the successive courses 1—1 are arranged with their vertically flanged joints 35 2—2 offset or staggered relative to each other. The plurality of interconnected wall sheets forming each of the successive courses are outwardly flanged at their top and bottom margins as at 3 for interconnection with the 40 adjacent courses of wall sheets. The interconnection of the successive courses of wall sheets may be effected by bolts or rivets engaging at spaced intervals abutting outstanding marginal flanges 3.

50 The assembled tank like structure is provided with a foundation or base 16 of concrete or the like, in which the lowermost course 1 of wall sheet is embedded. At opposite sides of the vertically disposed series of 55 access openings 17 the structure is reinforced by struts, located interiorly of the structure and extending from the top to the bottom thereof, with the lower ends also embedded in the concrete foundation 16. Whereas, the 60 usual and customary practice is to make every other course of wall sheets continuous, throughout the entire periphery of the structure, and to interrupt the intermediate courses of wall sheets to form spaced door openings one in each alternate course, the

present construction affords opportunity to make substantially as many access or door openings as there are courses of wall sheets, and yet each and every course is continuous throughout the entire periphery of the structure, so that the strains are uniformly distributed among the several courses. To this end the wall sheets of each course adjacent to the access opening 17 or that portion of each course projecting intermediate the vertical spaced angle bars 18 is reduced to tapered reinforced extremities 19 by folding the corners of the sheets backward upon themselves to parallelism, as shown at 20 in Fig. 5. The reversed corner folds of the successive course 70 sheet afford access openings 17, which are substantially rectangular, but arranged with their corners or diagonal access vertically disposed. These tapered ends of the courses reduced and reinforced by the reversed corner 75 laps 20 are further reinforced by introducing beneath such folded or reversed corners an angular insert plate 21, as shown in detail in Fig. 6. This reinforcement or insert plate 21 is provided with a plurality of rivet or bolt 80 holes registering with those of the folded wall plate, and for further reinforcement is provided with an outstanding bead or flange 85 22, formed by a reverse bend in the plate 21, adjacent to which is a series of bolts or rivet 90 holes 23, registering with corresponding holes in the vertical angle bar 18, to which the reinforcement plate is attached by bolts or rivets 95 extending through such holes and through the underlying wall sheets of the course. 100 The triangular or tapered extremities of each course of wall sheets project one toward the other intermediate the vertical angle bars 18, and are interconnected by channel shaped tie bars 24, as shown in Fig. 7. The tie bars 105 24 are of such material and so proportioned and designed that the cross sectional area of the tie channels 24 is substantially equal to the cross sectional area of the sheets forming the course of wall sheets interconnected by such 110 tie bars, so that the tensile strength of the tie bar and that of the wall sheet is substantially equalized. This tie bar is riveted or bolted to the reinforced tapered extremities of the course of sheets. The construction is such that 115 although the transverse tie channels 24 occupy but very small space intermediate the successive access openings 17, they will resist the internal pressure or bursting strain equally with the succession of wall sheets forming 120 the course. Thus each and every course of wall sheets is interconnected throughout the entire periphery of the structure and equal in strength and resistance to every other course. The front panel of the structure, including 125 the access openings and reinforced interconnected extremities of successive portions may be assembled at the factory complete, and the remaining wall sheets of each course interconnected thereto by the vertical joints 2—2. 130

However, if desired, the tie channels 24 may be riveted or otherwise secured at one end to one of the reduced tapered reinforced extremity of the course, while the other end is left free for attachment by bolting or other means at the time of erection of the structure. The reinforced tapered ends of the successive courses are of triple thickness, due to the reversal of the corners of the sheet, and the insertion of the reinforcement plate 21. Secured to the interior face of each of the channel tie bars 24, intermediate the reinforced ends of the sheet, are hinged blocks 25, shown in detail in Fig. 8. The ends of these blocks 25 are indented to receive the angles of the reinforced terminal extensions of the course sheets. Hinged or otherwise connected to these blocks 25 are closure doors 26, provided with buttons or pivoted fingers 27, which may be turned to locking position over the angular margin of the preceding course, of wall sheets. Each closure door 26 upon release of the button 27 may be turned inwardly and upwardly, or may be entirely removed by withdrawing the pintle pin connecting such door to the hinge block 25. This construction enables the access openings to be placed sufficiently close together that it is not necessary to lift the ensilage any appreciable extent in removing it from the silo, as is the case when the doors are located only in alternate courses of wall sheets, as shown in Fig. 21. The present construction affords the advantages of a substantially continuous access opening, to which the only interruptions are the comparatively narrow transverse tie channels 24. While but one vertical series of doors has been illustrated, it is obvious that additional access openings may be provided at any desired points without weakening the structure. At the same time, the structure possesses substantially the same resistance to bursting strain or internal pressure as it would if the successive courses of wall sheets were entirely continuous without provision of access openings.

While but one series of access openings or doors have been shown in the drawing, it will be understood that additional access openings may be provided at different points throughout the periphery of the silo wherever desired. The present construction is such that duplication of access or door openings does not reduce the strength or resistance of the silo wall. While if desired, the access openings may be closely spaced, as illustrated in the drawings, to afford substantially continuous openings, it will be understood that such construction is not essential, but one or more openings of such succession may be omitted by continuing the course of wall sheets intermediate successive openings. The transverse reinforcement or tie bars are necessitated only where doors or access opening are desired.

To form such spaced access or door open-

ings, instead of reversely folding both of the corners of contiguous ends of the course sheet as heretofore described, the lower corner only of the sheet forming one course and the upper corners only of the sheet forming the adjacent course may be reversely folded as shown at 23. This construction leaves the course sheets continuous throughout half their height so that they are better able to withstand the tension strain. The reverse corner flap 28 shown in Fig. 11 form V-shaped indentations in the adjacent courses of wall sheets 3, which when arranged in registry as shown in Fig. 12 form the access openings 17. Transverse tie bars or reinforcement bars 24' preferably of channel shape, but which may be merely angle irons are disposed horizontally above and below such access opening 17, the ends of the bars being connected by bolts or rivets with the vertical struts or studding bars 18 interiorly of the structure at each side of the opening.

As a further modification of this construction, instead of reversing or folding backwardly to parallelism the corners of the wall sheet to afford the access opening, such wall sheets may be horizontally split as indicated by the dotted line in Fig. 13, and the contiguous corners or flaps 29 formed thereby may be folded outwardly into parallelism with the main portion of the wall sheet 3 to afford the V-shaped indentation, which registering with a like indentation in the contiguous end of the adjacent wall sheets forming the same course, will afford the necessary access opening. A reinforcement plate 21' is inserted beneath the reverse corner-flaps of sheets forming successive courses, as shown at the bottom in Fig. 17. This reinforcement plate 21' thus overlaps the joint between successive courses of wall sheets 3, and has operative coupling engagement with the sheets of both courses. Transverse angle bars 30 are provided above and below the access openings or doors formed by such reverse triangular flaps 29. These angle bars 30 abut upon the outstanding flanges 3-3 forming the horizontal joints between successive courses and are connected by rivets or bolts to the vertical struts or studding bars 18, located interiorly of the structure at opposite sides of the access opening. This construction and arrangement of parts is clearly shown in Figs. 14 and 15. In addition to being connected to the angle bar struts or studding 18 and to the horizontal flanges of the wall sheets, such tie bars or reinforcement angles 30 are connected by rivets or bolts with the inserted triangular reinforcement plates 21' and their overlying wall sheet flaps 29. This affords a neat appearing construction, which will have maximum strength to resist the tension or bursting strain. Such reinforcement features indeed render the access opening panel of the structure of greater re-

sistance and strength than the continuous portions of the courses of wall sheets.

Cross reference is made to co-pending application, Serial No. 83,887 filed of even date herewith.

From the above description it will be apparent that there is thus provided a device of the character described, possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. In a silo or like construction, a cylindrical tank like structure, comprising a vertical succession of horizontal courses of interconnected wall sheets, said structure having a vertical succession of access openings, the adjacent ends of each succeeding course of wall sheets being interconnected intermediate the access openings.

2. In a silo or like construction, a cylindrical tank like structure, comprising a vertical succession of horizontal courses of interconnected wall sheets, said structure having a vertical succession of access openings, said openings being positioned in overlapping relation with succeeding courses of wall sheets, whereby each access opening extends partially into the zone of one course and partially into the zone of the adjacent course of wall sheets.

3. In a silo or like construction, a cylindrical tank like structure, comprising a vertical succession of horizontal courses of interconnected wall sheets, said structure having a vertical succession of access openings, said openings being so positioned that the zone of each horizontal course of wall plates will be intersected by portions of two access openings.

4. In a silo or the like construction, a cylindrical tank like structure having a vertical series of substantially rectangular access openings arranged with their diagonal corners in vertical alinement.

5. In a silo or like construction, a vertical succession of horizontal courses of wall sheets, the terminal sheets of each course being reversely tapered and interconnected to form a

succession of access openings between the tapered extremities of successive wall sheet courses.

6. In a silo or like construction, a cylindrical tank like structure, including a vertical 70 succession of horizontal courses of wall sheets having a vertical series of access openings, the wall sheets of each course adjacent to said openings being reduced in height and medial- 75 ly connected to form said openings.

7. In a silo or like construction, a tank like structure of sheet metal or the like, a pair of vertical spaced struts secured to the interior of the wall of such structure, and two series of substantially V-shaped wall extensions 80 projecting in oppositely arranged relation intermediate the struts, the opposite extensions of the respective series having their apices interconnected, thereby dividing the space intermediate the struts into a succession of 85 access openings.

8. In a silo or the like, a tank-like structure, including a panel comprising a succession of pairs of oppositely disposed tapered wall sections having the apices of the sections of each 90 pair interconnected to form a succession of intermediate access openings, and vertical frame members connecting the successive pairs of wall sections at opposite sides of the access openings.

9. In a silo or the like, a tank like structure including a panel comprising a succession of pairs of substantially V-shaped wall sections, the sections of each pair being reversely disposed and interconnected at their apices to 95 afford intermediate access openings.

10. In a silo or the like, a tank like structure, comprising a succession of horizontally disposed courses of wall sections including a vertical succession of interconnected reversely disposed substantially V-shaped extensions of each course of wall sections affording therebetween a succession of closely spaced access openings.

11. In a silo or the like, a tank like structure, comprising a succession of horizontally disposed courses of wall sections, including a vertical succession of interconnected reversely disposed substantially V-shaped extensions of each course of wall sections affording therebetween a succession of closely spaced access openings, said extensions being formed by folding the corners of wall sections forming said courses upon themselves to substantially parallelism to afford a reinforced tapered extension of multiple thickness.

12. In a silo or the like, a tank like structure comprising a succession of horizontally disposed courses of wall sections including a vertical succession of interconnected reversely disposed substantially V-shaped extensions of each course of wall sections affording therebetween a succession of closely spaced access openings, and similarly shaped 130

- reinforcement plates overlying the course extensions.
13. In a silo or the like, a tank like structure comprising a succession of horizontally disposed courses of wall sections including a vertical succession of interconnected reversely disposed substantially V-shaped extensions of each course of wall sections affording therebetween a succession of closely spaced access openings, pockets formed in said extensions by reversely bending portions of said course extensions upon themselves, and reinforcement plates engaged within the pockets thus formed.
14. In a silo or the like, a tank like structure comprising a succession of horizontally disposed wall courses, the successive courses having therein registering portions of reduced height to form intermediate access openings, reinforcement plates attached to said courses at opposite sides of said access openings and tie bars transversely connecting such reinforced portions of the successive courses.
15. In a construction of the character described, a course of wall sheets, the corners of adjacent sheets being reversely bent upon themselves to form two substantially V-shaped pockets, correspondingly shaped reinforcement plates in said pockets, transverse tie members connecting said reinforced pockets one to the other into a continuous annular body, such courses being superposed, one upon another to form a tank like structure, having a vertical succession of access openings formed intermediate said folded ends.
16. In a silo or the like, a tank like structure comprising a succession of horizontally disposed wall courses, a pair of vertically disposed spaced angle bars secured to the interior faces of said wall courses, and reduced extensions of the successive wall courses extending across the intervening space between said angle bars interconnecting the angle bars one with the other and connecting the successive courses into continuous annular sections, said reduced connecting extensions forming intermediate access openings to the interior of the structure.
17. In a silo or the like, a tank like structure comprising a succession of horizontally disposed wall courses, each course forming a continuous annular band, each course having formed therein oppositely disposed marginal indentations registering with like marginal indentations of succeeding courses to form intermediate access openings.
18. In a silo or the like, a tank like structure comprising a succession of horizontally disposed wall courses, each course forming a continuous annular band, certain courses having formed therein oppositely disposed marginal indentations registering with like marginal indentations of succeeding courses to form intermediate access openings, and means for reinforcing the indented portions of the wall courses to equalize the resistance of the course to bursting strains.
19. In a silo or the like, a tank like structure comprising a succession of horizontally disposed wall courses, each course forming a continuous annular band, certain courses having formed therein oppositely disposed marginal indentations registering with like marginal indentations of succeeding courses to form intermediate access openings, said indentations being formed by reversely folding flaps of the wall course material upon itself to form a reinforced section of reduced height.
20. In a silo or the like, a tank like structure comprising a succession of horizontally disposed wall courses, each course forming a continuous annular band, certain courses having formed therein oppositely disposed marginal indentations registering with like marginal indentations of succeeding courses to form intermediate access openings, vertically disposed angle bar struts secured to the wall courses at opposite sides of the registering indentations, and reinforcement means interconnecting said struts intermediate the access openings.
21. In a silo or like structure having sheet material walls, contiguous triangular flaps of the wall sheet material bent reversely into substantially parallelism with the wall sheets to leave between such reversed flaps of material, a polygonal access opening, the margins of which will be formed by the folds of such reversed flaps.
22. Reinforcement means for sheet material walls of silos and the like contiguous to access openings, including a series of sector like tongues of the material displaced to provide the opening, such tongues being bent reversely into substantially parallelism with the adjacent portions of the walls and reinforcing plates inserted within the pockets formed by the reversely bent tongues.
23. In a silo construction or the like, having sheet material walls, a group of reversely bent angular flaps of wall material surrounding an access opening in the walls of the structure, and forming reinforced margins about said opening.
24. In a silo construction or the like, having sheet material walls, a group of reversely bent angular flaps of wall material surrounding an access opening in the wall of the structure and forming reinforced margins about said opening, and reinforcement plates inserted beneath the reversely bent angular flaps.
25. In a silo construction or the like, having sheet material walls, a group of reversely bent angular flaps of wall material surrounding an access opening in the wall of the structure and forming reinforced margins about said opening, and reinforcement plates inserted beneath the reversely bent angular flaps.

plates inserted beneath the reversely bent flaps, the oppositely disposed plates being interconnected.

26. In a silo construction or the like, a tank like structure, comprising a succession of horizontal courses of sheet wall material, certain courses having therein substantially V-shaped notches formed by bending reversely into substantial parallelism with the wall 10 sheets angular flaps of the wall sheet material, the V-shaped notch of one course registering with that of a succeeding course to form an access opening to said structure.

27. In a silo construction or the like, a tank like structure having side walls formed from joined sections of sheet material certain contiguous sections of such sheet material having substantially V-shaped registering notches formed therein by bending reversely into 20 parallelism with the sections of wall material to form by said registering notches, an access opening to said structure.

28. In a silo construction or the like, a tank like structure, having side walls formed from joined sections of sheet material, certain contiguous sections having substantially V- 25

shaped registering notches formed therein to afford intermediate access openings to the interior of the structure.

29. In a construction of the character described, a wall for silos and the like, a pair of adjacently disposed triangular flaps formed by reversely bending portions of the silo wall material to parallelism, and a reinforcement plate common to two of said reversed flaps 30 35 and extending within the pocket formed thereby beneath said flaps.

30. In a construction of the character described, a wall for silos including interconnected succeeding sections of sheet material, contiguous flaps formed by reversely bending to parallelism portions of the respective succeeding sections and a reinforcement plate 40 45 extending across the joint between the sections and overlapping both sections, and projecting beneath the reversely bent flaps of both wall sections, substantially as specified.

In testimony whereof, I have hereunto set my hand this 5th day of January, A. D. 1926.

WILLIAM BAYLEY.
